UNITED STATES PATENT OFFICE.

EDWARD M. HEWLETT, OF SCHENECTADY, NEW YORK, ASSIGNOR TO GENERAL ELECTRIC COMPANY, A CORPORATION OF NEW YORK.

HIGH-VOLTAGE CIRCUIT INTERRUPTER.

Application filed August 16, 1926. Serial No. 129,329.

The invention relates to circuit interrupters particularly of the air brake type, and the object of the invention is to provide an improved form of air break circuit interrupter 5 having a magnetic arc extinguishing arrangement suitable for high voltage transmission line service.

In circuit interrupters adapted for high voltage service, such for example, as disconnecting switches intended for outdoor mounting, it has long been desirable to provide a magnetic blowout arrangement in order to obtain the advantages of quick interruption of the arc common in low voltage circuit interrupters. However, the usual outdoor location of high voltage switching apparatus, together with the insulation difficulties encountered, render the ordinary form of magnetic blowout arrangement employed in low voltage service utterly unfit for interrupting high voltage circuits. In low voltage service the magnetic blowout coil ordinarily is provided with a magnetic core, as well as magnetic pole pieces extending into 25 close proximity to the arc. Such an arrangement is not adapted for high voltage service, particularly in alternating current transmission lines due not only to the difficulty of suitably insulating the magnetic circuit of 30 the blowout from the high voltage transmission lines, but also from the disturbing influence of the relatively high inductance inherent in iron core blowout coils.

My present invention provides an improved 35 high voltage circuit interrupter of a form adapted to be embodied in transmission line switching systems and having a magnetic arc blowout construction and arrangement whereby the advantages of magnetic arc extinguishment may be attained successfully in 40 high voltage service. In carrying out my present invention in a preferred form the high voltage circuit interrupter is constructed with a suitable high voltage outdoor type of strain insulator interposed between the movable switch member and the stationary switch contact for maintaining 45 the two in operative relation and at the same time providing a support for a transmission line circuit conductor that is electrically and mechanically connected to the stationary switch contact. In order to provide a magnetic arc blowout for the high voltage circuit interrupter, an arcing member is supported 50 and insulated from the stationary switch con-

tact and the circuit conductor and by means of suitable outdoor type insulators with the arcing member in arcing relation with the movable switch member. An elongated blowout coil is located adjacent the arcing 60 member and is electrically connected between the arcing member and the switch contact, together with the line conductor connected thereto, so as to be energized in series circuit with the arc between the movable switch member and the arcing member. Thus, it will be seen that my improved form of high voltage magnetic blowout switch is well adapted for high voltage transmission line switching service and the magnetic blowout insures a 70 quick and effective suppression of arcing upon operation of the switch.

In the accompanying drawing Fig. 1 shows diagrammatically a high voltage line disconnecting switch embodying the invention in a 75 preferred form, and Fig. 2 shows a modification of the invention embodied in a feeder line disconnecting switch.

Referring to Fig. 1 it will be seen that the high voltage transmission line circuit interrupter comprises a pair of movable switch elements 11 and 12 which are pivotally mounted upon the ends of the support 13 secured to a suitable high voltage insulator 14. The movable switch arms 11 and 12 are operated 80 simultaneously into and out of engagement with the cooperating stationary contact members 15 and 16 by means of the operating devices 17 and 18 which operate through the agency of suitable lever and toggle mechanism 19, as indicated in the drawing. The stationary switch contact 15 is connected to a support by the movable switch member 11 by means of the high voltage insulator 20, which preferably is in the form of a plurality 85 of interconnected insulator units, as indicated in the drawing, although other forms of high voltage insulators may be employed if desired. The stationary switch contact 15 is mechanically connected to support the 90 transmission line conductor L¹ by means of the insulating elements 21, the arcing member 22 and the insulating element 23, and the stationary switch contact 15 is electrically connected to the line conductor L¹ by the jumper 95 24. The insulating elements 21 and 23, as well as the insulating member 20, are shown as of the high tension insulator type, and serve to anchor the line conductor L¹ to the support 13 upon which the movable members 100 105 110

11 and 12 are mounted and, at the same time, maintain the stationary contact 15 in operating relation with the movable switch member 11 and also the arcing member 22 in arcing relation with the movable switch member 11.

In order to provide for magnetic extinguishment of the arc in accordance with the present invention, a blowout coil 25, preferably of the elongated form, as indicated in the drawing, is located adjacent the arcing member 22 and electrically connected between the arcing member 22 and the stationary switch contact 15, as well as the line conductor L^1 , so that the coil 25 is energized by the current flowing in the arc between the arcing member 22 and the movable switch member 11. The coil 25 is connected in the circuit as indicated by the arrows in the drawing so as to set up a strong magnetic field about the arcing member 22 in such direction that the arc is rapidly moved to the left along the member 22 and extended upwards therefrom as indicated by the dotted lines in the drawing. The stationary switch contact 16 likewise is mechanically connected to the support 13 on the movable switch element 12 with the high voltage insulator 26 interposed between the support and the switch contact for maintaining the latter in operative relation with the movable switch element 12. Also the line conductor L^2 is mechanically supported from the stationary switch element 16 through the strain insulator 27, the arcing member 28 and the strain insulator 29, and is electrically connected to the stationary contact 16 by the jumper 30. The elongated blowout coil is disposed between the jumper 30 and the arcing member 28 and electrically connected therebetween so as to set up a magnetic field about the arcing member 30 in a manner similar to that previously described.

From the foregoing it will be evident that upon actuation of the operating member 18 the movable switch elements 11 and 12 are operated into engagement with the switch contacts 15 and 16 to complete a circuit between the line conductors L^1 and L^2 . If now the operating element 17 is operated the switch members 11 and 12 are returned to the open position in which they are shown and any arcing occurring upon the opening of the switch is quickly extinguished by operation of the blowout coils 25 and 30. The arc drawn between the movable switch element 11 and the contact 15 readily springs to the upturned end 22^a of the arcing member 22 extending over the top of the strain insulator 23. As a result the blowout coil 25 is connected in series circuit with the arc extending between the arcing member 22 and the movable switch member 11. The resulting flow of current through the blowout coil 25 sets up a magnetic field that rapidly moves

the arc to the left along the top of the arcing member 22 until the arc becomes attenuated and breaks the circuit. Likewise, the arc spring between the movable switch element 12 and the upturned end 28^a of the arcing member 28 is rapidly moved to the right along the arcing member and extended in the form indicated by the dotted lines until the arc finally breaks. Due to the fact that the blowout coils 25 and 30 are located on opposite sides of the movable switch members, any action of the wind tending to prevent the blowing out of the arc on one of the movable switch members serves to expedite the extinguishment of the arc from the other switch member irrespective of the direction of the wind.

The modified circuit interrupter illustrated in Fig. 2 is particularly adapted for use as a disconnecting switch for feeder lines from an overhead high voltage transmission line. In this arrangement the movable switch elements 41 and 42 are pivotally mounted upon the bottom of the high voltage insulator 43 and are simultaneously operated into and out of engagement with the cooperating switch contacts 44 and 45 by means of the operating elements 46 and 47 and the lever and toggle mechanism 48. The high voltage tension insulator 43, preferably composed of interconnected units as illustrated, is interposed between the movable switch members 41 and 42 and the cooperating contacts 44 and 45 for the purpose of maintaining the latter in operative relation with the former.

The switch contacts 44 and 45 are mechanically and electrically connected to the line conductor L^2 and the arcing members 50 and 51 are supported and insulated from the line conductor L^2 by suitable high voltage insulators 52 and 53. The elongated blowout coils, similar to the form shown in Fig. 1, are disposed between the arcing members 50 and 51 and the line conductor L^2 , as indicated in the drawing, and are electrically connected to be energized by the current in the arcs extending from the movable switch members 41 and 42 to the arcing members 50 and 51 upon the opening of the switch. The respective blowout coils are so connected and arranged that each is connected in series circuit with the arc and sets up a magnetic field about the arcing member with which it is associated in such direction as to move the arc extending between the arcing member and the corresponding movable switch member upward and outward as indicated in the dotted lines in the drawing.

Upon the opening of the switch arms 41 and 42 the circuit extending through the line conductors L^1 and L^2 is opened and any arc between the movable switch elements 41 and the contact 44 immediately jumps to the arcing member 50. Likewise, any arcing be-

tween the movable switch element 22 and the contact 45 is transferred to the arcing member 51. The combined current in the arc passes through each of the arcing coils 54 and 55 and the resulting magnetic action rapidly attenuates the arc until it is broken.

What I claim as new, and desire to secure by Letters Patent of the United States, is:

1. A high voltage air break switch comprising relatively movable switch elements, means for supporting at least one of said switch elements from the line conductor to be connected thereto including a high voltage tension insulator extending between the elements and secured thereto for maintaining the same in spaced operative relation, an arcing member mounted on insulating supports to be supported from the line conductor to receive one end of the arc from said one of said switch elements and extending in arcing relation with the other of the switch elements, and an elongated air core blowout coil electrically connecting the arcing member and the said one switch element to be included in series circuit with the arc and disposed adjacent said arcing member for magnetically expanding the arc extending between the member and the other switch element.

2. A high voltage air break switch comprising a movable switch member, a cooperating stationary switch contact and a circuit conductor mechanically and electrically connected thereto for supporting the same, a tension insulator for maintaining the stationary switch contact in operative relation with the movable switch member, an arcing member supported by said circuit conductor and insulated from said stationary switch contact and said circuit conductor in arcing relation with the movable switch member, and an air core blowout coil disposed adjacent to said arcing member and electrically connecting the arcing member with the stationary switch contact and the circuit conductor so as to be included in series circuit with the arc.

3. A high voltage air break switch comprising a switch member pivotally mount-

ed upon an insulating support, a cooperating stationary contact mechanically and electrically connected to a circuit conductor to be supported thereby, a strain insulator extending between the movable switch member and the stationary contact for maintaining the stationary switch contact with the circuit conductor connected thereto in operative relation with the movable switch member, an arcing member supported from said circuit conductor with one end mounted adjacent said stationary switch contact and insulated therefrom and the other end adjacent said circuit conductor and insulated therefrom with the arcing member in arcing relation with the movable switch member, and an elongated air core blowout coil disposed in substantially parallel relation with said arcing member and connected to be included in series circuit with the arc for magnetically extending the arc therealong.

4. A multiple break high voltage circuit interrupter comprising a pair of movable switch members mounted upon an insulating support and each operable into and out of engagement with a cooperating stationary switch contact, an insulator extending between each of the movable switch members and the corresponding stationary switch contacts for maintaining the same in operative spaced relation, a line conductor electrically connected to each switch contact and arranged to be mechanically supported thereby, an arcing member supported by and insulated from each stationary switch contact and the line conductor associated therewith in cooperating relation with a corresponding one of said movable switch members, and an air core blowout coil disposed adjacent each arcing member and connected to be energized by the current flowing in the arc between the movable switch members and the arcing members upon the opening of said switch member.

In witness whereof, I have hereunto set my hand this 13th day of August, 1926.

EDWARD M. HEWLETT.
